DISPLAY STAND FOR WIG BLOCKS

Myron E. Mencimer, Rte. 5, P.O. Box 778,
Golden, Colo. 80401

Filed Mar. 17, 1971, Ser. No. 125,446

Term of patent 14 years

Int. Cl. D6—06

U.S. Cl. D6—28

FIG. 2

FIG. 3

FIG. 1 is a side elevational view of a display stand for wig blocks embodying my new design;

FIG. 2 is a side elevational view of a display stand for wig blocks as shown in FIG. 1; and

FIG. 3 is a top plan view of FIG. 1.

I claim:

The ornamental design of a display stand for wig blocks, substantially as shown and described.
